MATTRESS AND RECEPTACLE ADJUSTER

Harold Lloyd Chapman, East Moriches, N. Y.

Application April 15, 1941, Serial No. 388,701

5 Claims. (Cl. 5—72)

This invention relates to beds and more particularly to an apparatus for adjusting mattresses.

It is an object of the present invention to provide a device for selectively adjusting the position of the mattress to afford a predetermined posture for the occupant of the bed.

A further object of the invention is to provide such a device with means for adjustably positioning a receptacle in the bed.

Further and more specific objects will plainly appear from the detailed specification and drawings presented herewith in exemplification and not in limitation of the invention.

Like reference characters represent like members in the accompanying drawings, wherein:

Fig. 1 shows a plan view of the apparatus attached to the side rails of a bed or a bed spring;

Fig. 2 is a perspective view of a detail of the end bearing and crank positioned on the right hand side of the bed when viewed from the foot of the bed as shown in Fig. 1;

Fig. 3 is a side elevation of the left hand side of the bed shown in Fig. 1 with the apparatus in its flat position;

Fig. 4 is a like view of the apparatus in its elevating position;

Fig. 5 is a perspective fragmentary view of a preferred means for slidably attaching the receptacle to the apparatus; and

Fig. 6 is a perspective view of a preferred means for supporting the apparatus independently of the bed.

The apparatus shown in Fig. 1 comprises a mattress elevating member 10 positioned beneath the mattress 15 and a mattress depressing member 19 overlying the top of the mattress 15. The elevating member 10 is provided with two parallel crank arms 11 joining the shafts 20 which are carried by the journal members 12 in the bearings 13 affixed by attaching means 15 to the rails 14. The rails 14 may be the side rails of the bed or of the spring frame. One end of the shaft 20 is provided with a crank arm 16 affixed thereto at 17. When the apparatus is in its flat position as shown in Fig. 3, the arm 16 is substantially parallel to the rail 14 as shown in Fig. 2. To the other end of the shaft 20 is affixed the lever 25 which has an extension 26 of approximately the same length or throw as the arm 16. Resilient means such as relatively stiff springs are shown at 18 releasably connecting the outer end of the arms 16 and 26 with the depressions of the depression member 19. The depression member 19 may be provided with a guide

21 having a longitudinal guideway 22 adapted to rotatably, slidably and removably engage a rod 32 affixed to the receptacle or bed pan 31. The lever 25 is provided with a spring detent 27 adapted to engage a series of apertures 28 in the quadrant 28. The elevating member 10 may be preferably provided with a pressure distributing plate 23 adapted to be detachably, adjustably and rotatably positioned to support the small of the back of the patient or occupant of the bed. The plate 23 is held on the elevating member 10 by means such as the spring clips 24.

In operation, the apparatus may be permanently or detachably affixed to the rails 14 of the bed or bed springs with the elevation member 10 remaining in a flat position beneath the mattress 15 and with the lever 25 in its flat position substantially parallel to the rails 14. When it is desired to adjust the mattress 15 the removable depression member 19 is affixed in its coacting position on top of the mattress 15 by means of releasable connections with the springs 18. Thereafter the crank 25 may be moved upwardly until the detent 27 positions it at the elevation desired. As the crank 25 moves upwardly the elevating member 10 raises the underside of the mattress 15 at an area or portion approximately beneath the small of the back of the occupant of the bed and at the same time the depression member 19 depresses the portion of the mattress 15 approximately below the waist of the occupant so that the mattress 15 assumes in profile a concurrently elevated and depressed position which permits the patient to assume the posture most comfortable and most convenient for the use of the receptacle or pan 31. Thereafter the pan 31 may be slidably removed from the guideway 22 and the depression member 19 likewise detached and removed and the lever 25 depressed to its horizontal position which will permit the mattress 15 to resume its normal flat position. When the lever 25 is in this flat position the detent 27 is positioned at the upper end 30 of the quadrant 28 beyond the last aperture 29 therein. This permits the lever 25 to have a slight floating movement within that unapertured upper portion 30 of the quadrant 28 and prevents the elevating member 10 in this flat position from distorting the position of the mattress 15 in cases where it is desired to leave the depression member 19 also in place when the pan 31 is not in use.

The novel apparatus herein described may be incorporated in a household bed or in a hospital bed of any type either with or without the adjustable or foldable bed spring or bed frame

members and it also may be used with equal advantage with or without the pan. When used without the pan it may also be advantageously employed as a means for providing a reading or eating posture for bedridden patients throughout the day.

A preferred means for supporting the apparatus in its operating position independently of any attachment directly to the bed is shown in Fig. 6, which discloses a preferred support or stand 45. The stand 45 may preferably comprise tubular leg members 39 joined by a cross brace 40 at their lower ends and supporting at their upper ends the bracket 36. The brace 40 may preferably be joined with a like brace member 42 on the opposite legs of the stand by means of the rod 44. The brace member 42 connects each of the foot members 46 which are adapted to separably engage the leg members 41 to which are affixed at their upper ends the bracket 47. To the bracket 47 is affixed journal bearing 37 which carries rotatable shaft 38 having at one end a clutch member 39, and to the other end is affixed the arm 16.

To the bracket 36 is affixed the quadrant 28 and the journal member 48, which carries the rotatable shaft member 35. To the other end of the shaft member 35 is affixed the clutch member 34.

In this modification of the invention, each end of the shaft 20 has affixed thereto a clutch member shown at 33 and 49 adapted to interfit the clutch members 34 and 39.

In operation, the preferred supporting means just described may be conveniently used to operate the novel apparatus herein described independently of any attaching means to the bed in the following manner:

When the leg members 41 are disconnected from the foot members 46, by means of the stud and socket joint 43 the stand 45 may be placed in position with the legs 39 and the foot members 46 on opposite sides of the bed with the brace member 44 extending under the bed. Next, the shaft 20 may be engaged by means of the clutch members 34, 39, 33 and 49 so that the plate 23 is positioned beneath the mattress. Thereafter the legs 41 may be inserted in the foot members 46. The apparatus is now in position to have the depression member 19 attached to the arms 16 and 26 by means of the springs 18 in a manner previously described herein.

The present invention of course contemplates that the lever member 25 in all embodiments of the invention may be positioned on either side of the bed that may be convenient to the user. The legs 39 and 41 may be provided with floor gripping means 50 in the form of rubber grips which may be made removable and interchangeable with the usual casters that may be substituted for the rubber grips when the apparatus is not in use on a mattress.

The present invention contemplates all modifications and equivalents within the spirit and scope of the appended claims.

What is claimed is:

1. For use with a bed having side rails supporting a mattress, mattress adjusting apparatus detachably secured to said bed, said apparatus comprising a mattress elevating member positioned beneath said mattress, a mattress depressing member overlying said mattress, said elevat-

ing means being positioned to elevate that portion of the mattress approximately beneath the small of the back of the occupant of the bed, said depressing means being positioned to depress that portion of the mattress approximately below the waist of the occupant, means for slidably and removably adjusting a receptacle along said depressing means, means releasably and detachably connecting said elevating means and said depressing means, and means for concurrently operating said elevating means and said depressing means.

2. Apparatus of the class specified comprising in combination with a bed having bed springs and a mattress thereon, an elevating member adapted to extend transversely across the bed beneath the mattress and between the latter and the bed springs, a depressing member adapted to extend transversely across the upper side of the mattress, means connecting said members in spaced relation longitudinally of the mattress, means for actuating said members substantially simultaneously to raise said elevating member and lower said depressing member to thereby raise the upper portion of the mattress while maintaining the lower portion thereof below said depressing member in a substantially normal or horizontal plane, and releasable means adapted to hold said members in selected elevated and depressed positions.

3. The combination of claim 2, wherein said elevating member is in the form of a rod having a centrally positioned back plate attached thereto serving to distribute the pressure of the rod over a greater area with respect to the mattress.

4. Apparatus of the class specified comprising in combination with a bed having bed springs and a mattress thereon, an elevating member adapted to extend transversely across the bed between the mattress and bed springs, a depressing member adapted to extend transversely across the bed on the upper side of the mattress and in spaced relation longitudinally of the latter with respect to said elevating member, actuating means operatively connecting said members to one another and adapted to simultaneously raise said elevating member and depress said depressing member, means releasably holding said members in a selected elevated or depressed position, and means for adjustably and removably positioning a receptacle on said depressing member.

5. Apparatus of the class specified comprising, in combination with a bed having a bed spring and a mattress thereon, a mattress elevating member adapted to extend transversely across the bed between the mattress and bed spring, a depressing member adapted to extend transversely across the upper side of the mattress and in spaced relation longitudinally of the latter with respect to said elevating member, actuating means operatively connecting said members in spaced relation longitudinally of the mattress and adapted to elevate said elevating member and depress said depressing member, releasing means for holding said members in a selected elevated or depressed position, said actuating means including a resilient connection with said depressing member whereby the latter is held in its depressed position under tension.

HAROLD LLOYD CHAPMAN.
